UNITED STATES PATENT OFFICE.

TITO LIVIO CARBONE, OF GRUNEWALD, NEAR BERLIN, GERMANY.

ELECTRIC-ARC LAMP.

SPECIFICATION forming part of Letters Patent No. 737,343, dated August 25, 1903.

Application filed February 7, 1903. Serial No. 142,387. (No model.)

To all whom it may concern.

Be it known that I, TITO LIVIO CARBONE, a subject of the King of Italy, residing at Grunewald, near Berlin, in the Kingdom of 5 Prussia, German Empire, have invented certain new and useful Improvements in Arc-Lamps; and I do hereby declare that the following is a full, clear, and exact description of the invention.

10 The present invention relates to an arc-lamp.

The invention consists in the construction, combination, and arrangement of parts herein-after described, and particularly pointed out 15 in the claim.

One mode of construction of the new arc-lamp is shown on the annexed drawings.

Figure 1 is a front view. Fig. 2 is the corresponding side view. Fig. 3 is a plan view. 20 Fig. 4 is a section on line A B of Fig. 2.

The support 2 is fastened on the carrier-plate 1, three rods 3 4 5 being inserted in the former. A foot-piece 6 is fastened on the lower end of said rods and holds the base-25 plate 7, under which the arc is formed. The rods 3 4 are arranged at an inclination one to the other corresponding to the inclination of the carbon rods, while the rod 5 stands vertically. The rod 5 passes through a hole 8 of 30 the sliding plate 9, and the rods 3 and 4 each pass through a hole provided in each of the clamps 10, supporting the carbon rods of the upper electrode. The clamps 10 slide on the front side of the sliding plate 9 and are sus-35 pended on the screw-bolt 12 of the sliding plate 9 by means of links 11. A band 13, attached on the sliding plate 9, is wound on the pulley 14, with which a second pulley 15, containing the band 16, is rigidly connected.

40 The pulleys 14 15 are insulated one from the other and are fastened on a common axle 17, journaled in the frame 18, which is pivotally mounted on a support 20. The support 20 is fastened on the carrier-plate 1 and bears the 45 standard 21, on which the frame 18 rests in its lowest position. An electromagnet 23 is provided above the frame 18 by means of a support 22. As soon as the electromagnet receives current it attracts the armature 24, 50 fastened on the frame 18, so that the latter

rocks on the pivot 19. The carrier 26 of the lower carbon rod 27 is suspended on the band 16, wound on the pulley 15 within the guiding-tube 25. The two carbon rods 28 29 of the upper electrode are inserted in the clamps 55 10 and touch one another at their lower ends, the carbon rods being guided near to their lower ends in an opening of the foot-piece 6. The whole device is arranged in such a way that the carbon electrodes have the right distance for the arc if the frame 18 rests on the standard 21. The diameters of the pulley 14 and 15 are chosen at such a relation that the carbon 27 is raised exactly the same amount as it burns off. The upper carbons 28 29 sink 60 automatically, owing to the weight of the sliding plate 9 as they burn off, so that the arc is always formed at the same place under the base-plate.

When the arc-lamp is inserted in the circuit, the electromagnet 23, which is shunted with regard to the arc, attracts its armature 24 and lifts the frame 18. The lower electrode is thus more raised than the upper one, since the distance of the band 16 from the 75 pivot 19 is greater than that of the band 13 from the pivot 19. As soon as the lower electrode touches the upper one the shunted electromagnet 23 receives less current, so that it drops the armature 24. The frame 18 comes 80 again to rest on the standard 21, so that the lamp burns with an arc of the proper length. The sliding plate 9 sinks at the same rate as the upper electrode, consisting of the two inclined carbon rods 28 29, burns off, so that the points 85 of these carbons touch one another always at the same place underneath the base-plate 7, because the clamps 10 are suspended by means of links 11 and because they are guided always in the same direction by the 90 rods 3 4. The band 16, carrying the lower electrode, is wound up on the pulley 15 as the sliding plate 9 sinks.

Having now described my invention and in what manner the same is to be performed, 95 what I claim, and desire to secure by Letters Patent, is—

An arc-lamp, the upper electrode of which consists of two carbon rods, inclined together at an acute angle and suspended by links on 100

a sliding plate, which automatically sinks by its own weight, as the carbons burn off, the lower electrode consisting of a single carbon, suspended on a pulley rotating with a second pulley, which is connected to said sliding plate by means of a band, substantially as shown and described.

In witness whereof I have hereunto set my hand in presence of two witnesses.

TITO LIVIO CARBONE.
